ABSTRACT

A training magazine has a body configured to be removably received in the magazine well, a motor connected to the body and having a rotating shaft, an actuator operably engaged to the reciprocating action element, and operable to reciprocate the reciprocating action element, a linkage interconnecting the motor to the actuator, the linkage including a rotor operably connected to the rotating shaft and operable to rotate in response to rotation of the rotating shaft, and a link connected to the body and operably connected to reciprocate in response to rotation of the rotor to generate reciprocation of the actuator. The link is pivotally connected to the body at a first portion comprising a first end and a second portion is a second end opposite the first end. The rotor may operably engage the link at an intermediate position between the first and second ends.

TRAINING MAGAZINE

**CROSS-REFERENCE TO RELATED
APPLICATION**

This application is a Continuation-in-Part of U.S. patent application Ser. No. 17/737,420 filed on May 5, 2022, entitled "TRAINING MAGAZINE," which claims the benefit of U.S. Provisional Patent Application No. 63/188,798 filed on May 14, 2021, entitled "FIREARM TRAINING APPARATUS AND METHODS OF USING," which is hereby incorporated by reference in its entirety for all that is taught and disclosed therein.

FIELD OF THE INVENTION

The present invention relates to firearms, and more particularly to a training magazine that enables repeated dry firing of a firearm without having to retract the slide or other trigger resetting system or device of the firearm.

**BACKGROUND AND SUMMARY OF THE
INVENTION**

When dry firing a fully functioning firearm, typically performed during a training exercise, traditionally the firearm's trigger mechanism remains in the fired position without resetting after each time the trigger is pulled. Thus, a shooter practicing dry firing must pull back the slide, hammer, charging handle, or other trigger resetting system and/or device of the firearm after each shot because a round was not fired to reset the mechanism. This results in an unnatural training experience for many types of semi-automatic and fully automatic firearms because nonstandard manipulations of the firearm are required between shots.

Therefore, a need exists for a new and improved training magazine that enables repeated dry firing of a firearm without having to retract the slide or other trigger resetting system or device of the firearm. In this regard, the various embodiments of the present invention substantially fulfill at least some of these needs. In this respect, the training magazine according to the present invention substantially departs from the conventional concepts and designs of the prior art, and in doing so provides an apparatus primarily developed for the purpose of enabling repeated dry firing of a firearm without having to retract the slide or other trigger resetting system or device of the firearm.

The present invention provides an improved training magazine, and overcomes the above-mentioned disadvantages and drawbacks of the prior art. As such, the general purpose of the present invention, which will be described subsequently in greater detail, is to provide an improved training magazine that has all the advantages of the prior art mentioned above.

To attain this, the preferred embodiment of the present invention essentially comprises a body configured to be removably received in the magazine well, a motor connected to the body and having a rotating shaft, an actuator operably engaged to the reciprocating action element, and operable to reciprocate the reciprocating action element, a linkage interconnecting the motor to the actuator, the linkage including a rotor operably connected to the rotating shaft and operable to rotate in response to rotation of the rotating shaft, and a link connected to the body and operably connected to reciprocate in response to rotation of the rotor to generate reciprocation of the actuator. The link is pivotally connected to the body at a first portion comprising a first end and a

second portion is a second end opposite the first end. The rotor may operably engage the link at an intermediate position between the first and second ends. There are, of course, additional features of the invention that will be described hereinafter and which will form the subject matter of the claims attached.

There has thus been outlined, rather broadly, the more important features of the invention in order that the detailed description thereof that follows may be better understood and in order that the present contribution to the art may be better appreciated.

BRIEF DESCRIPTION OF THE DRAWINGS

15 FIG. 1 is a top isometric view of the current embodiment of a training magazine constructed in accordance with the principles of the present invention.

FIG. 2 is an exploded view of the training magazine of FIG. 1.

20 FIG. 3 is an isometric side sectional view of the training magazine of FIG. 1 in use installed in the magazine well of a pistol.

FIG. 4 is a front sectional enlarged view of the training magazine of FIG. 1.

FIG. 5 is an enlarged isometric view of the motors, gear train, energy storage element, and input rotor of the training magazine of FIG. 1.

FIG. 6A is a side view of the training magazine of FIG. 1 with the actuator in the resting or start of travel position.

30 FIG. 6B is a side view of the training magazine of FIG. 1 with the actuator at the half travel position.

FIG. 6C is a side view of the training magazine of FIG. 1 with the actuator at the full travel position.

FIG. 6D is a side view of the training magazine of FIG. 1 with the actuator in the process of rapidly returning to the resting or start of travel position shown in FIG. 6A.

FIG. 7 is a rear isometric view of the control mechanism of the training magazine of FIG. 1.

FIG. 8A is a side view of an alternative embodiment of a 40 training magazine constructed in accordance with the principles of the present invention with the actuator in the forward resting or start of travel position.

FIG. 8B is a side view of the alternative embodiment of the training magazine of FIG. 8A with the actuator at the half travel position.

FIG. 8C is a side view of the alternative embodiment of the training magazine of FIG. 8A with the actuator at the full travel position.

FIG. 8D is a side view of the alternative embodiment of the 50 training magazine of FIG. 8A with the actuator in the process of rapidly returning to the resting or start of travel position shown in FIG. 8A.

FIG. 9 is a side view of the alternative embodiment of the training magazine of FIG. 8A showing how the alternative embodiment of the training magazine interacts with the slide of a pistol.

FIG. 10 is a top sectional view of the alternative embodiment of the training magazine of FIG. 8A.

The same reference numerals refer to the same parts 60 throughout the various figures.

**DESCRIPTION OF THE CURRENT
EMBODIMENT**

An embodiment of the training magazine of the present invention is shown and generally designated by the reference numeral 10.

FIGS. 1-5 illustrate the improved training magazine 10 of the present invention. More particularly, in FIG. 3, the training magazine is shown installed in a firearm 12 having a frame 14 defining a magazine well 16. The firearm includes a reciprocating action element 18 responsive to actuation of a trigger 20. The training magazine has a body 22 configured to be removably received in the magazine well. A motor 24 is connected to the body and is operable to generate a motive force. In the current embodiment, there are two motors. The motors can be solenoid motors, servomotors, a DC rotary motor, or an AC rotary motor. An energy storage element 26 is operably connected to the motor and is configured to store potential energy generated by the motive force. An actuator 28 is operably engaged to the energy storage element and to the reciprocating action element. The actuator is operable to transmit the potential energy to reciprocate the reciprocating action element via a hook 54 (shown in FIG. 3). The hook extends from the actuator engages a face 56 (shown in FIG. 3) on the reciprocating action element that would normally support the case head, and would also normally strip a cartridge from a conventional magazine.

In the current embodiment, the reciprocating action element 18 is a pistol slide, and the energy storage element 26 is a spring having a plurality of loops about a common axis that interconnects the motor 24 and the actuator 28. The spring is preferably a torsion coil spring having a cylindrical shape with opposed circular ends 30, 32. An input rotor 34 is operably connected to the motor and to a first end of the spring. The input rotor is connected to two motors by a gear train 46 in the current embodiment. An output rotor 36 is operably connected to an output end of the spring and to the actuator. The spring is received within the input and output rotors. The spring could also be a flat coil spring where the input rotor is connected to the inner end of the flat coil spring, and the output rotor is connected to the outer end of the flat coil spring, or vice versa. A control element 38 is connected to the output rotor and is operable to limit the rotation of the output rotor in terms of both the rotation rate and the total amount of rotation. In the current embodiment, the control element is a motorized worm gear, and the total amount of rotation is limited to one complete rotation. A pivoting lever 40 is connected to the output rotor and is configured to generate a reciprocating motion in response to rotation of the output rotor. This is accomplished by an eccentric cam 48 on the output rotor that is received within an elongated aperture 50 defined by the pivoting lever. A control mechanism 42 that is illustrated in FIG. 7 and will be described subsequently is responsive to motion of the trigger 20 to enable motion of the actuator. A battery pack 44 contained in an extended baseplate portion 52 of the body 22 is connected to the motor to provide a power source. The battery pack can contain a lithium-ion battery or conventional replaceable batteries, and may be weighted so the training magazine 10 simulates the weight of a traditional loaded magazine.

The energy storage element 26 is operable to store energy from the motor 24 before releasing the energy to the actuator 28. The motor is operable to generate a selected amount of potential energy in the energy storage element over a first interval, and wherein the energy storage element is operable to generate motion of the actuator and reciprocate the reciprocating action element 18 over a shorter second interval. Thus, the motor is operable to flex the spring over a first interval, and the spring is operable to generate motion of the actuator and reciprocate the reciprocating action element over a shorter second interval. The input rotor 34 rotates

only in a single direction as the reciprocating action element reciprocates. The output rotor 36 rotates only in a single direction as the reciprocating action element reciprocates. The energy storage element is free of any fixed connection to the body 22, such that all portions of the energy storage element move as the reciprocating action element reciprocates.

The training magazine 10 can allow for a finite number of shots before requiring the user to simulate reloading of the firearm 12. The training magazine can leave the firearm completely operational except that no ammunition is being fired when the trigger is pulled. The firearm's safety function can be unaffected by the training magazine.

When the firearm 12 is fired with the training magazine 10 installed, there is no discharge of a cartridge to provide energy to cycle the reciprocating action element to reset the firearm for another shot. Instead, as is shown in FIGS. 6A-D, the stored energy in the energy storage element 26 is released once the trigger 20 is pulled to enable the actuator 28 to pull the reciprocating action element rearward to reset the firearm for another shot. FIG. 6A shows the actuator in the resting or start of travel position. Once the trigger is pulled, the output rotor rotates and pivots the pivoting lever 40 rearward such that the actuator moves rearward and begins to pull the reciprocating action element rearward. FIG. 6B shows the actuator at the half travel position, and FIG. 6C shows the actuator at the full travel position. When the actuator has reached the full travel position, the reciprocating action element has been pulled rearward to the maximum extent. At the full travel position, the stored energy being released from the energy storage element is no longer sufficient to overcome the force exerted by the return spring of the firearm. Thus, the reciprocating action element rapidly pulls the actuator forward as shown in FIG. 6D to return the actuator to the resting or start of travel position shown in FIG. 6A and to reset the firearm for another shot. In the current embodiment, the training magazine can reset the firearm at a rate of 10 shots per second, which is sufficient to simulate the normal firing rate of semi-automatic firearms and some fully automatic firearms.

Optionally, the firearm's normal return spring can be replaced with a weaker spring to reduce the force and power requirements of the training magazine 10. The force reduction could be enough that the eccentric cam 48 would also force the pivoting lever 40 and actuator 28 forward, rather than simply allowing the return spring to return the reciprocating action element 18 to battery without assistance. The return spring could also be removed entirely, and the eccentric cam would provide all of the force to return the reciprocating action element to battery.

FIG. 7 illustrates the improved control mechanism 42 of the training magazine 10. More particularly, the control mechanism has a lever 58 that is connected to the actuator 28. When the firearm 10 is fired, the firing pin 60 impacts the lever. The lever actuates a detector switch 62 on a circuit board 64 in the training magazine, which then activates the training magazine to move the reciprocating action element 18. Alternatively, the lever could directly release the output rotor 36 when the lever is struck by the firing pin.

As a further alternative, a lever arm, switch, and circuit board can be contained by a housing that is shaped to mimic the shape of a normal barrel in the firearm, and which replaces the barrel in this embodiment. When the firing pin impacts the lever arm, the switch is activated on the circuit board. Activation of the switch turns on an optical transmitter (in this case, infrared), which may or may not be modulated. An optical receiver in the training magazine

detects this optical signal and activates the training magazine to move the reciprocating action element.

FIGS. 8A-10 illustrate an alternative embodiment of the improved training magazine 100 of the present invention. More particularly, in FIG. 9, the training magazine is shown as if the training magazine were installed in a firearm 12 having a frame 14 defining a magazine well 16. The firearm includes a reciprocating action element 18 responsive to actuation of a trigger 20. The training magazine has a body 122 configured to be removably received in the magazine well. A motor 124 is connected to the body and is operable to generate a motive force. In the current embodiment, there are two motors to provide balanced drive. The motors can be solenoid motors, servomotors, a DC rotary motor, or an AC rotary motor. An actuator 128 is operably engaged to the reciprocating action element. The actuator is operable to reciprocate the reciprocating action element via a hook (not visible). The hook extends from the actuator engages a face (not visible) on the reciprocating action element that would normally support the case head, and would also normally strip a cartridge from a conventional magazine.

In the current embodiment, the reciprocating action element 18 is a pistol slide. An input rotor 134 is operably connected to the motor. The input rotor is connected to two motors by a gear train 146 in the current embodiment. An output rotor 136 is operably connected to the actuator. A pivoting lever 140 is connected to the output rotor and is configured to generate a reciprocating motion in response to rotation of the output rotor. This is accomplished by an eccentric cam 148 on the output rotor that is received within an elongated aperture 150 defined by the pivoting lever. A control mechanism 142 that is illustrated in FIG. 9 and will be described subsequently is responsive to motion of the trigger 20 to enable motion of the actuator. A battery pack (not visible) contained in an extended baseplate portion (not visible) of the body 122 is connected to the motor to provide a power source. The battery pack can contain a lithium-ion battery or conventional replaceable batteries, and may be weighted so the training magazine 100 simulates the weight of a traditional loaded magazine.

The input rotor 134 rotates only in a single direction as the reciprocating action element reciprocates. The output rotor 136 rotates only in a single direction as the reciprocating action element reciprocates.

The training magazine 100 can allow for a finite number of shots before requiring the user to simulate reloading of the firearm 12. The training magazine can leave the firearm completely operational except that no ammunition is being fired when the trigger is pulled. The firearm's safety function can be unaffected by the training magazine.

When the firearm 12 is fired with the training magazine 100 installed, there is no discharge of a cartridge to provide energy to cycle the reciprocating action element to reset the firearm for another shot. Instead, as is shown in FIGS. 8A-D, the motor 124 operates once the trigger 20 is pulled to enable the actuator 128 to pull the reciprocating action element rearward to reset the firearm for another shot. FIG. 8A shows the actuator in the resting or start of travel position. Once the trigger is pulled, the output rotor rotates and pivots the pivoting lever 140 rearward such that the actuator moves rearward and begins to pull the reciprocating action element rearward. FIG. 8B shows the actuator at the half travel position, and FIG. 8C shows the actuator at the full travel position. When the actuator has reached the full travel position, the reciprocating action element has been pulled rearward to the maximum extent. At the full travel position, the motor stops operating. Thus, the reciprocating action

element experiences the force exerted by the return spring of the firearm and rapidly pulls the actuator forward as shown in FIG. 8D to return the actuator to the resting or start of travel position shown in FIG. 8A and to reset the firearm for another shot. In the current embodiment, the training magazine can reset the firearm at a rate of 10 shots per second, which is sufficient to simulate the normal firing rate of semi-automatic firearms and some fully automatic firearms.

Optionally, the firearm's normal return spring can be replaced with a weaker spring to reduce the force and power requirements of the training magazine 100. The force reduction could be enough that the eccentric cam 148 would also force the pivoting lever 140 and actuator 128 forward, rather than simply allowing the return spring to return the reciprocating action element 18 to battery without assistance. The return spring could also be removed entirely, and the eccentric cam would provide all of the force to return the reciprocating action element to battery.

It should be appreciated that the input rotor 134, output rotor 136, and gear train 146 are a linkage interconnecting the motor 124 to the actuator 128. The input and output rotors can be combined into a single rotor. The input rotor is operably connected to a rotating shaft on the motor that forms part of the gear train and is operable to rotate in response to rotation of the rotating shaft. The pivoting lever 140 is a link connected to the body 122 and operably connected to the input rotor by the output rotor to reciprocate in response to rotation of the input rotor to generate reciprocation of the actuator 128. The pivoting lever is pivotally connected to the body at a first portion including a first end 156, and a second portion is a second end 158 opposite the first end. The output rotor operably engages the pivoting lever at an intermediate position 160 between the first and second ends. The output rotor includes the eccentric cam 148, which operably engages the link. The body is an elongated body defining a body axis 162. The motor is a pair of motors having parallel axes 164, 166 extending parallel to the body axis. The body is an elongated body defining a major side plane 168. The motor is a pair of motors having parallel axes 164, 166 extending parallel to the major side plane. The body has opposed major side panels 170, 172, and the pair of motors is closely received between the side panels.

The reciprocating action element 18 includes a firing pin 45 responsive to the trigger 20. The control mechanism 142, which is located in the reciprocating action element, includes an electronic module 174 having a switch 176 operably responsive to the firing pin. The electronic module includes a transmitter 178. The body includes a receiver 180 configured to receive a trigger signal from the transmitter. The receiver is operably connected to the motor 124 and operable to operate the motor to reciprocate the reciprocating action element in response to the trigger signal. The trigger signal can be an infrared emission. The transmitter 55 can be an infrared emitter, and the receiver can be an infrared receiver. In the event the trigger signal is an infrared emission, the transmitter and receiver must be arranged so that their line of sight clears internal features of the firearm 12.

In the context of the specification, the terms "rear" and "rearward," and "front" and "forward," have the following definitions: "rear" or "rearward" means in the direction away from the muzzle of the firearm while "front" or "forward" means it is in the direction towards the muzzle of the firearm.

While current embodiments of a training magazine have been described in detail, it should be apparent that modifi-

cations and variations thereto are possible, all of which fall within the true spirit and scope of the invention. Although semi-automatic pistols have been disclosed, the training magazine is also suitable for use with fully automatic pistols, semi-automatic and fully automatic rifles, and other firearms. The current embodiments as complete training firearms. With respect to the above description then, it is to be realized that the optimum dimensional relationships for the parts of the invention, to include variations in size, materials, shape, form, function and manner of operation, assembly and use, are deemed readily apparent and obvious to one skilled in the art, and all equivalent relationships to those illustrated in the drawings and described in the specification are intended to be encompassed by the present invention.

Therefore, the foregoing is considered as illustrative only of the principles of the invention.

Further, since numerous modifications and changes will readily occur to those skilled in the art, it is not desired to limit the invention to the exact construction and operation shown and described, and accordingly, all suitable modifications and equivalents may be resorted to, falling within the scope of the invention.

We claim:

1. A training magazine for a firearm having a frame defining a magazine well, and a reciprocating action element responsive to actuation of a trigger, the training magazine comprising:

a body configured to be removably received in the magazine well;

a motor connected to the body and having a rotating shaft; an actuator operably engaged to the reciprocating action element, and operable to reciprocate the reciprocating action element; a linkage interconnecting the motor to the actuator;

the linkage including a rotor operably connected to the rotating shaft and operable to rotate in response to rotation of the rotating shaft; and

the linkage including a link connected to the body and operably connected to reciprocate in response to rotation of the rotor to generate reciprocation of the actuator.

2. The training magazine of claim 1 wherein the link is pivotally connected to the body at a first portion comprising a first end and a second portion is a second end opposite the first end.

3. The training magazine of claim 2 wherein the rotor operably engages the link at an intermediate position between the first and second ends.

4. The training magazine of claim 1 wherein the rotor includes an eccentric cam operably engaging the link.

5. The training magazine of claim 1 wherein the body is an elongated body defining a body axis, and wherein the motor comprises a pair of motors having parallel axes extending parallel to the body axis.

6. The training magazine of claim 1 wherein the body is an elongated body defining a major side plane, and wherein the motor comprises a pair of motors having parallel axes defining a motor axis plane extending parallel to the major side plane.

7. The training magazine of claim 6 wherein the body has opposed major side panels and the pair of motors is closely received between the side panels.

8. A training firearm comprising:
a frame defining a magazine well;
a reciprocating action element movable to reciprocate with respect to the frame;
a trigger; a magazine having a body configured to be removably received in the magazine well;
a motor connected to the body and having a rotating shaft;
an actuator operably engaged to the reciprocating action element, and operable to reciprocate the reciprocating action element;
a linkage interconnecting the motor to the actuator;
the linkage including a rotor operably connected to the rotating shaft and operable to rotate in response to rotation of the rotating shaft; and
the linkage including a link connected to the body and operably connected to reciprocate in response to rotation of the rotor to generate reciprocation of the actuator.

9. The training firearm of claim 8 wherein the link is pivotally connected to the body at a first portion comprising a first end and a second portion is a second end opposite the first end.

10. The training firearm of claim 9 wherein the rotor operably engages the link at an intermediate position between the first and second ends.

11. The training firearm of claim 8 wherein the rotor includes an eccentric cam operably engaging the link.

12. The training firearm of claim 8 wherein the body is an elongated body defining a body axis, and wherein the motor comprises a pair of motors having parallel axes extending parallel to the body axis.

13. The training firearm of claim 8 wherein the body is an elongated body defining a major side plane, and wherein the motor comprises a pair of motors having parallel axes defining a motor axis plane extending parallel to the major side plane.

14. The training firearm of claim 13 wherein the body has opposed major side panels and the pair of motors is closely received between the side panels.

15. The training firearm of claim 8 wherein the reciprocating action element includes a firing pin responsive to the trigger, and the reciprocating action element includes an electronic module having a switch operably responsive to the firing pin.

16. The training firearm of claim 15 wherein the electronic module includes a transmitter and wherein the body includes a receiver configured to receive a trigger signal from the transmitter.

17. The training firearm of claim 16 wherein the receiver is operably connected to the motor and operable to operate the motor to reciprocate the actuator in response to the trigger signal.
